(57) **CLAIM**

The ornamental design for an air pump for an airbed, as shown and described.

DESCRIPTION

FIG. 1 is a top perspective view of an air pump for an airbed showing our new design;

FIG. 2 is a bottom perspective view thereof;

FIG. 3 is a first side view thereof;

FIG. 4 is a second side view thereof;

FIG. 5 is a third side view thereof;

FIG. 6 is a fourth side view thereof;

FIG. 7 is a top view thereof;

FIG. 8 is a bottom view thereof;

FIG. 9 is an enlarged side view of the portion marked '9' of FIG. 1; and,

FIG. 10 is an enlarged view of the portion marked '10' of FIG. 2.

The dot-dash broken lines encircling portions of the air pump for an air bed in FIGS. 1 and 2 and illustrated in enlarged views in FIGS. 9 and 10 form no part of the claimed design.

The broken lines shown in the drawings represent portions of the air pump for an air bed that form no part of the claimed design.
